(57) **CLAIM**

The ornamental design for a plasma hand torch, as shown and described.

DESCRIPTION

FIG. 1 is a downward front perspective view of the design for a plasma hand torch;

FIG. 2 is an upward rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines in the drawings illustrate portions of the plasma hand torch that form no part of the claimed ornamental design.
